(57) **CLAIM**

The ornamental design for a display screen or portion thereof with transitional graphical user interface, as shown and described.

DESCRIPTION

FIG. 1 is a first image in a sequence for a display screen or portion thereof with transitional graphical user interface showing our new design in accordance with a first embodiment;

FIG. 2 is a second image thereof;

FIG. 3 is a third image thereof;

FIG. 4 is a fourth image thereof;

FIG. 5 is a first image in a sequence for a display screen or portion thereof with transitional graphical user interface showing our new design in accordance with a second embodiment;

FIG. 6 is a second image thereof;

FIG. 7 is a third image thereof; and,

FIG. 8 is a fourth image thereof.

The appearance of the transitional image sequentially transitions between the images shown in FIGS. 1-4 and FIGS. 5-8. The process or period in which one image transitions to another forms no part of the claimed design. The outermost broken lines in the figures depict a display screen or portion thereof and form no part of the claimed design. The remain-
